UNITED STATES PATENT OFFICE.

CHARLES H. HODGES, OF DETROIT, MICHIGAN, ASSIGNOR TO THE DETROIT STEAM RADIATOR COMPANY, OF SAME PLACE.

DESIGN FOR A RADIATOR.

SPECIFICATION forming part of Design No. 18,313, dated May 15, 1888.

Application filed June 10, 1887. Serial No. 240,953. Term of patent 7 years.

To all whom it may concern:

Be it known that I, CHARLES H. HODGES, a citizen of the United States, residing at Detroit, in the county of Wayne and State of Michigan, have invented and produced a new and original Design for Radiators, of which the following is a specification, reference being had to the accompanying drawings, forming part thereof.

10 In the drawings, Figure 1 is a view in elevation of a single pipe or loop radiator illustrating my design, and Fig. 2 is a perspective view of a multiple-loop radiator having the same arrangement and variety of ornamentation.

15 My design consists in a radiator having a section of ornamental leaves at the bottom of each vertical radiator pipe or loop and a section of ornamental leaves between the top and 20 bottom of each vertical loop.

A designates the section of ornamental leaves between the bottom and top of a single pipe or loop radiator, and B the section of ornamental leaves at the bottom of said vertical loop, while A' and B' designate the corresponding ornamental features of the multiple loop radiator.

25 What I claim is—

The design for a radiator, which consists in a section of ornamental leaves at the bottom of each vertical radiator pipe or loop and a section of ornamental leaves between the top and bottom of each vertical loop, as herein shown and described.

30 In testimony whereof I sign this specification in the presence of two witnesses.

CHARLES H. HODGES.
